UNITED STATES PATENT OFFICE.

LUCIUS E. JOHNSON, OF ROANOKE, VIRGINIA.

RAILROAD SCOOP-CAR.

1,078,289.

Specification of Letters Patent. Patented Nov. 11, 1913.

Application filed June 2, 1912. Serial No. 706,708.

To all whom it may concern:

Be it known that I, LUCIUS E. JOHNSON, a citizen of the United States, residing at Roanoke, in the county of Roanoke and 5 State of Virginia, have invented certain new and useful Improvements in Railroad Scoop-Cars; and I do hereby declare the following to be a full, clear, and exact description of the invention, such as will enable others 10 skilled in the art to which it appertains to make and use the same.

This invention relates to railway cars and particularly to the type known as "scoop cars" wherein a shovel or scoop is attached 15 to the end of the car to be forced into or under debris on the track in order to remove such debris from the track upon the scoop, the scoop resting upon the track at its forward end when being loaded and being 20 raised at said forward end from the track and carried away with the car to a point where the debris is to be unloaded therefrom. A car of this type was patented to L. E. Johnson, June 14, 1904, numbered 25 762,314, in which the scoop was hinged to the end of a car, the pivot pin being arranged transversely to the car and track whereby the front end might be raised off the track when loaded, in a vertical plane 30 parallel with the track, and the sides of the scoop were hinged to the base plate in order that they might be lowered to positions in line with the base plate to permit the load to be removed from the scoop at the sides 35 thereof and of the track by shoveling or other manually operated means.

The present invention is in the nature of an improvement upon the subject matter of the aforesaid patent, and its object is to 40 increase the utility of such devices by providing means for carrying and loading a scoop as in said patented construction, and in addition thereto, means whereby the unloading of the scoop is facilitated by eliminating the necessity of any manually operated unloading devices such as shovels and the like.

With these objects, and other objects which will hereinafter appear, in view, the 45 invention consists in the improved construction, arrangement and combination of the parts of a scoop car which will be herein-after fully described and afterward specifically claimed.

50 In order that the construction and operation of the invention may be readily com-

prehended, I will now proceed to particularly describe an approved embodiment thereof which I have illustrated in the accompanying drawings, and in which,—

Figure 1 represents, in side elevation, an end of a car, parts being broken away, and the scoop being shown in longitudinal section, hinged to the car with its front end resting on the track rails in position to be forced under debris on the track. Fig. 2 represents, in perspective, on a reduced scale the end of a car with a scoop hinged thereto, with its front end raised from the track in the position to be carried away with the 70 car to be dumped. Fig. 3 represents, in perspective, the parts shown in Fig. 2, the scoop being shown in dumping position. Fig. 4 represents, in plan, on an enlarged scale, one half of the base plate of the scoop, 75 detached from the car, showing the details of construction. Fig. 5 represents, in side elevation, a scoop detached from the car, the rear lower corner being broken away. Fig. 6 represents, in longitudinal section, the 80 scoop-carrying plate by means of which it is hinged to the car, showing the details of construction. Fig. 7 represents, in plan view, one longitudinal half of the scoop-carrying plate, detached from the car. Fig. 85 8 represents, in side elevation, the scoop-carrying plate. Fig. 9 represents, in vertical longitudinal section, on an enlarged scale, a portion of the front end of the car to which the scoop is to be hinged, showing the 90 details of construction. Fig. 10 represents, in vertical transverse section, on an enlarged scale in partial dumping position, the details of construction being shown.

Like reference characters indicate the same 95 parts, wherever they appear in any of the figures of the drawing.

A car equipped in accordance with my invention carries a suitable engine or motor which will be referred to hereinafter, but 100 inasmuch as such engine or motor may be of any approved type and forms no part of the invention proper, I have not deemed it necessary to illustrate it. The general details of construction of the car, which may 105 be of any approved type have also been omitted in the drawings except where they are directly connected to and constructed to operate with the scoop and its operative mechanism.

110 Referring specifically to the drawings, 1 indicates the floor of the car, 2 and 3 the

longitudinal side beams, and 4 the front-end cross beam, to the front face of the latter of which, depends a metallic plate 5, to the front face of which is secured, by means of 5 suitable bolts 6, a casting 7, which supports the coupling 8 (Fig. 9).

At a short distance from the front end of the car a suitable inclined beam or bracket 9 is secured to each side of the car frame by 10 bolts 10, 11, and at the forward lower ends of these inclined beams or brackets, a supplementary cross beam 12 is supported, by means of suitable plates or castings 13 and bolts 14 and 15, the bolts 15 passing through 15 the beam 12 and plate 5.

By removing the securing bolts and nuts, the supplementary beam 12 may be readily removed and replaced, or a new one substituted when desired, such supplementary beam forming no part of the main frame of 20 the car.

The construction of the parts of the front end of the car may be varied from that described, the object being to provide a strong 25 support for the supplementary cross beam 12 which receives great strain during the operation of the scoop as will be hereinafter described. Suitably secured and projecting below and in front of the said supplementary 30 cross beam 12, at each side of the car, is a bracket 16, which forms one member of the two-hinge connections for the scoop-carrying or supporting plate as hereinafter described, each of said brackets 16 being 35 provided with a horizontal slot, as at 17.

At 18 is indicated the scoop-carrying or supporting plate, which is of suitable strong construction, being provided at its front end with a transverse bearing plate 19 to rest 40 upon the track when the scoop is being thrust into the debris on the roadway, and at its rear end with depending ears 20 having openings 21 through which, and the slots 17, is passed the horizontal transverse pin 22, 45 by means of which the plate is pivotally connected to the front end of the car, whereby said plate is permitted to be raised at its forward end off the track for the purposes stated.

50 The scoop-carrying or supporting plate 18 is provided with a vertical rear end plate 23, secured by rivets, Fig. 6, or other suitable means, in position to contact with the additional removable cross beam 12, so that the said cross-beam will receive the rearward end thrust or strain put upon the supporting plate and scoop when the latter is forced into the debris and thereby loaded, thereby relieving the main frame, and especially the 55 main end beam 4, of the wear and injury incident to such end thrust and avoiding the necessity of removing and replacing or renewing of said cross beam 4 or other parts of the main frame. The supporting plate

is further provided with rigid sides 24 and 65 with transverse bars or narrow plates 25, 26, riveted to the plate and having vertical ends 27, 28, riveted to the sides and projecting above them and provided with horizontal, longitudinal tubular ends or barrels 29, 30, 70 at their upper ends, the barrels 29 on each end receiving a pin 31 hereinafter referred to, and the barrels 30 being arranged in pairs to receive between each pair a similar barrel 32 at the lower end of a vertical strap 75 33 riveted to the sides 34 of the scoop 35, said sides being either integral with or rigidly secured to the base plate or bottom 36 of the scoop. The barrels 30 and 32 receive removable pins 37, which, when the scoop 80 is supported on the carrying or supporting plate 18, form the means whereby the scoop is held on the supporting plate, as in Figs. 1 and 2, but which, when the scoop is to be dumped laterally, as hereinafter described, 85 form hinge pins or pintles, those on one side of the scoop being removed when the scoop is to be dumped on the opposite side of the track, as in Fig. 3. Vertical straps 38 are also riveted to the sides of the scoop and 90 carry at their lower ends, barrels 39 for purposes hereinafter described.

Riveted to the bottom or base plate of the scoop are bars 40 which project beyond the forward end of the scoop and have their forward projecting ends 41 sharpened or pointed in order to facilitate the entrance of the scoop into the debris, the forward ends of the sides of the scoop, as at 42, sloped off from top to bottom for the same purpose, 100 and the edges of the said sides being strengthened and reinforced by means of strips or bars 43 riveted thereto.

The car, when equipped for operating this invention, is provided with a roof or covering 44 suitably supported, and strengthened by braces 45, to cover the upper bearing, at 46, for the hollow rotary post 47 of a derrick, the boom 48 of which projects out of the open end of the car, over the scoop and 110 its supporting plate, said boom being suitably braced, at 49. On the hollow post 47, near its lower bearing on the car body, is fixed a horizontal pulley 50 connected, by a suitable cable or belt 51 with the engine or 115 motor heretofore mentioned but not illustrated, whereby the post may be rotated and the boom swung around from side to side above the scoop.

On the rotary post 47, below and in line 120 with the boom are secured bearing brackets 52 for a pulley 53, which projects through a vertical slot into the hollow post, the inner periphery of the pulley being in the central axial line of the post, and, below the lower 125 end of the hollow rotary post, a pulley 54 is mounted in bearings on the car body, the front side of the periphery of said pulley

being in the vertical line of the central axis of the hollow post and of the inner periphery of the pulley 53.

At the outer end of the boom 48 are journaled two pulleys, 55, side by side, and a cable or belt 56 from the engine or motor is passed under pulley 54, up the hollow post 47, around or over the pulley 53, outward to the end of the boom, and over one of the pulleys 55, whence it passes down and around a central pulley 57 journaled in a doubletree 58, thence up again and around the other pulley 55 at the end of the boom, and again down to a bail 59 which straddles the doubletree and is pivotally engaged on the ends of the journals of the pulley 57. At each end of the doubletree 58 is suspended a bail 60.

By the means described the boom may be swung around to bring the doubletree into position above the front end, on either side of the scoop. In order to raise the forward end of the supporting plate 18, and consequently, the scoop, off the track when it is desired to move the car, with scoop attached, the boom is swung around to the position shown in Fig. 2, and the bails 60 are straddled over barrels 29, on plates 27, on the sides of the carrying plate 18, and the pins 31 slipped into the bails and barrels, in which position, the forward end of the supporting plate will be supported clear of the rails. During the removal of the car and loaded scoop to the dumping place, the parts will be in position just described with the pins 37 engaged in the barrels 30 and 32 on both sides of the scoop and its supporting plate, firmly holding these parts together. When, however, the dumping place is reached, the bails 60 are disengaged by the withdrawal of the pins 31, the pins 37 withdrawn from the barrels 30 and 32 on the side opposite to that on which the scoop is to be dumped, the hollow post partially rotated to swing the boom around to a position above the side of the scoop on which the pins 37 have been withdrawn, the bails 60 straddled over the barrels 29 and the pins 61 inserted in said bails and barrels. By now operating the engine or motor, the engaged side of the scoop will be raised off the supporting plate 18, the still engaged pins 37 on the opposite side serving as hinge pins or pintles. When the operation is proceeding, the hollow post may also be rotated and the boom swung around toward the dumping side, and the free side of the scoop carried around on its pintles until the dumping position of Fig. 3 is reached, when the contents of the scoop will be dumped on the side of the track and the scoop emptied without the employment of shovels or like tools, the economy of time and labor being obvious. To restore the

scoop and its supporting plate to their positions, as in Fig. 1, ready for another operation, it is only necessary to reverse the movement of the boom, disengage the doubletree, reinsert pins 37, reengage the doubletree with the front end of the scoop supporting plate, and raise the latter off the track to the position of Fig. 2.

The construction and operation of the invention will be readily comprehended from the foregoing without further description, and the improvement over the former cited patent will be obvious, and while I have described specifically the construction and operative relation of the various parts, it will be obvious to those skilled in this art that many slight changes and variations may be made therein, without departing from the spirit and scope of the invention.

Having thus described my invention, what I claim as new is:

1. In combination, a scoop-supporting plate adapted to be hinged to the end of a car, a scoop, and means for removably hinging the scoop along either side to the supporting plate.

2. In combination, a scoop-supporting plate adapted to be hinged to the end of a car, a scoop, means for removably hinging the scoop along one side to the supporting plate, and means for securing the scoop along its opposite side to the supporting plate.

3. In combination, a car, a scoop-supporting plate connected thereto by a hinge having a transverse pintle, and a scoop connected to the supporting plate by hinges having longitudinal pintles.

4. In combination, a car, a scoop-supporting plate connected thereto by a hinge having a transverse pintle, and a scoop connected to the supporting plate on either side by hinges having longitudinal pintles.

5. In combination, a car, a scoop-supporting plate connected thereto by a hinge having a transverse pintle, and a scoop connected to the supporting plate on both sides by hinges having removable longitudinal pintles.

6. In combination, a car, a scoop supporting plate, a hinge having a transverse pintle connecting the plate to the car, a scoop, a hinge with a longitudinal pintle hinging one side of the scoop to one side of the plate, and a second hinge having a removable longitudinal pintle securing the other side of the scoop to the other side of the plate.

7. In combination, a car provided with a frame comprising a main end beam, a supplementary end beam secured below the main end beam, a scoop support connected to the supplementary end beam, a scoop on the support, and means whereby the support may swing on its connection with the sup-

plementary beam in a longitudinal vertical plane to raise the outer end of the scoop off the track.

8. In combination, a car provided with a frame comprising a main end beam, a supplementary end beam secured below the main end beam, a scoop support connected to the supplementary end beam, a scoop on the support, means for raising the scoop support, and hinged connections along the sides for securing the scoop to its support, said hinged connections being releasable whereby when one of them is raised, the scoop may be dumped laterally on the other connection as a hinge.

9. In combination, a car provided with a frame, comprising a main end beam, a supplementary end beam secured below the main end beam, a scoop support connected to the supplementary end beam, a scoop on the support, means for raising the scoop support, hinged connections along the sides for securing the scoop to its support, said hinged connections being releasable whereby when one of them is raised, the scoop may be dumped laterally on the other connection as a hinge, and means for tilting the scoop on said hinge connections in a transverse vertical plane.

10. In combination a car, a scoop hingedly connected to one end thereof to swing in a longitudinal vertical plane and to rest with its outer end on the track, and means carried by the car for raising the outer end off the track and for tilting the scoop sidewise, said means comprising a derrick having a rotary post and a boom extending outwardly from said post over the scoop.

11. In combination, a car, a scoop supporting plate hinged to one end thereof, straps secured to the plate near the front end thereof terminating in barrels, a derrick carried by the car, a doubletree suspended from the derrick, bails suspended at the ends of the doubletree and adapted to straddle the barrels, and a pin adapted to be passed through each bail and its straddled barrel.

12. In combination, a car, a scoop hingedly connected to one end thereof and constructed to tilt sidewise, straps on one side of

the scoop terminating in barrels, a derrick carried by the car, a doubletree suspended from the derrick, bails suspended from the ends of the doubletree adapted to straddle the bails, and a pin adapted to be passed through each bail and its straddled barrel.

13. In combination, a car, a scoop hingedly connected to one end thereof and constructed to tilt sidewise, straps on both sides of the scoop terminating in barrels, a derrick carried by the car; a doubletree suspended from the derrick, bails suspended from the ends of the doubletree adapted to straddle the bails of either sides, and a pin adapted to be passed through each bail and its straddled barrel.

14. In combination, a car, a scoop-supporting plate hinged to the end thereof, a scoop supported on the plate and adapted to tilt sidewise, straps at the outer end of the plate terminating in barrels, straps on one side of the scoop terminating in barrels, a derrick carried by the car, a doubletree suspended from the derrick, bails suspended from the doubletree and adapted to straddle the barrels of the supporting plate, or the barrels of the scoop, and a pin for each bail adapted to pass through the bail and its straddled barrel.

15. In combination, a car, a scoop-supporting plate hinged to the end thereof, a scoop supported on the plate and adapted to tilt sidewise, straps at the outer end of the plate terminating in barrels, straps on both sides of the scoop terminating in barrels, a derrick carried by the car, a doubletree suspended from the derrick, bails suspended from the doubletree and adapted to straddle the barrels of the supporting plate, or the barrels of either side of the scoop, and a pin for each bail adapted to pass through the bail and its straddled barrel.

In testimony whereof, I have signed my name to this specification in the presence of two subscribing witnesses.

LUCIUS E. JOHNSON.
